UNITED STATES PATENT OFFICE.

EDWARD LINDSLEY, OF CLEVELAND, OHIO.

STREET-BOX AND SHUT-OFF FOR WATER, GAS, OR OTHER FLUID SERVICE.

SPECIFICATION forming part of Letters Patent No. 383,472, dated May 29, 1888.

Application filed April 7, 1887. Serial No. 234,072. (No model.)

To all whom it may concern:

Be it known that I, EDWARD LINDSLEY, a citizen of the United States, residing at Cleveland, in the county of Cuyahoga and State of Ohio, have invented certain new and useful Improvements in Street-Boxes and Shut-Offs for Water, Gas, and other Fluid Service; and I do hereby declare that the following is a full, clear, and exact description of the invention, which will enable others skilled in the art to which it appertains to make and use the same.

The invention relates to improvements in street-boxes and shut-offs for water, gas, and other fluid service; and it consists in a box and associate parts, substantially as shown and described, and particularly pointed out in the claims.

In the accompanying drawings, Figure 1 is a vertical central section of the box and hydrant attachments. Fig. 2 is a similar view at right angles to the first, with the hydrant attachments omitted and the screw top or plug which closes the top of the box and the extra bushing for the key in position. Fig. 3 is a plan view of the box complete with the top and extra bushing in position, as in Fig. 2. Fig. 4 is a perspective of the tap or plug, and Fig. 5 a perspective of the bushing separately. Fig. 6 is a perspective and Fig. 7 a plan view of the plug which covers the drip-orifice in the box. Fig. 8 is a perspective and Fig. 9 a plan view of the valve in the bottom of the box. Fig. 10 shows the lower end of the key which is seen in suspended position in Fig. 1. Fig. 11 is a view of the upper section of the hydrant with a fluid-pressure gage attached to the spout or nozzle.

The device here shown is designed to be employed in the distribution of water, natural gas, illuminating-gas, oil, and other fluids to residences and other places, and is constructed with special reference to simplicity and convenience, as well as to overcome material objections in street-boxes and street shut-offs as heretofore made. These shut-offs and the service-pipes are designed to be located below the frost-line in the earth, so as to protect said parts from the action of the frost; but the boxes that extend to the surface and through which the internal mechanism is reached and controlled necessarily are exposed to the frost

and liable to be damaged or permanently impaired thereby.

It may be said to be the object of the first part of my invention to obviate this difficulty and to make surface connections or boxes which are proof against frost and differences or changes in temperature. This is effected by making the box-tubing in sections, as shown. Thus we have a lower section, A, including in this case a part of the shut-off mechanism, the upper section, B, having its top portion about the usual height in relation to the surface of the earth, and the intermediate pipe or tube, C, extending, as shown, into each of the sections A, B, and packed with lead or other suitable packing within said sections. At its lower end the tube C rests in a thimble, D, which in turn is supported on a ledge or annular shoulder, a, in the section A. By this construction I dispense with the screw-thread connections heretofore used in this character of devices, and which are objectionable because they are rigid and cannot yield under the influence of frost, and substitute connections which, while they are equally effective in confining the fluid, will readily accommodate themselves to the action of the frost at either connection and sustain no damage when freezing occurs.

E is the shut-off valve. (Shown most clearly in Fig. 8.) This valve has two seating-surfaces, e e', the surface e being adapted to rest against the upper seat, a', when the passage-way through the vertical tubing is closed, and the surface e' resting upon the lower seat, a'', when for any reason it is desired to stop the flow of fluid through the service-pipes F G. If the said valve is adjusted to an intermediate position between the two seats a' a'', the fluid will be free to flow through the service-pipes and into the vertical tubing as well. For the latter purpose the valve is provided with a transverse slot or opening, e'', extending through from side to side above the upper seating-surface, e, and above the diaphragm e'' therein, and the interior of the valve is open from that point to the top. Above the transverse slot e'' on its outside the valve is screw-threaded to engage the screw-threads on the casing or tube A, and on its inside at e''' is a key-seat adapted to be engaged by the key K,

whereby the said valve may be adjusted to any position between its respective seats at pleasure.

Above the valve E is a screw-plug, L, open 5 through the center for the free passage of the fluid, and having a head with an annular bevel at l, which fits snugly upon the seat l' on the casing. The seat l' is tapped by a drain-passage, l'', which, when the plug L is raised and 10 the valve E is seated to prevent the flow of fluid into the vertical tubing, serves to drain the fluid from said tubing and to prevent freezing therein. The sole function of the plug L is to control the drain passage or opening, and 15 it is provided with a key-seat, l''', in its upper interior portion, to be engaged by the key K in the same manner as the valve E. Between the key and valve, and partly in each, as indicated by the letters e^o and l^o, respectively, is 20 an annular chamber, in which the angular head K' of the key is adapted to turn, so as to enable it to be entered into the seat in the valve E, and to be removed therefrom through the plug L. Normally the plug L will be 25 seated, as shown, and will only be raised when the tubing is to be cleared of its contained fluid.

In Fig. 1 I show an extra section or joint, M, attached to the tubing of the box as an extension thereof, and which is aboveground for 30 convenience in attaching hose or making other connections therewith at m. When this section is employed, the structure serves the purpose of a hydrant. Any length or form of extension other than that shown can be adopted, 35 if desired, and when not in use may be replaced by the cap or top shown in Fig. 4. When the fluid is drawn through the joint M, or what may be termed the "hydrant," the valve will of course be lowered somewhat to permit 40 the fluid to rise in the hydrant; but this will not close the passage between the service-pipes.

Another important advantage in this construction is the facility it offers for detecting 45 leakage or water waste in the service-pipes beyond the shut-off. Suppose, for example, that the pipe G connects with a residence. If the shut-off is closed against the admission of water from the main, it will of course open the hydrant to the back flow and pressure of the water from the residence. Then, if a suitable 50 pressure-gage has been attached to the nozzle or outlet of the hydrant, as shown in Fig. 11, it will at once record the pressure of the fluid 55 in the residence, and by leaving the gage in position for a time the fact of leakage, if any, will be accurately recorded on the gage. In this way the condition of the pipes in a building can be ascertained in the street and without 60 entering the building, which will be of great convenience to water-inspectors, as well as avoiding annoyance to occupants of dwellings when inspections are made.

O, Fig. 4, is a plug or tap adapted to close 65 the top of the box when the section M is not used. This plug is screwed down into the

box flush with its top, and has an annular chamber provided with recesses o opposite each other. These recesses are designed to afford catches or locks for the bushing P. 70 (Shown in Fig. 5.) The bushing P consists of two sections, p, having lugs p', which engage the recesses o, as shown in Fig. 2, angular faces p'', which form a key-seat, and a spring, p''', which connects the sections. When the 75 bushing is in position on the box, as seen in Fig. 3, a key-seat is formed corresponding to the seats in the plug L and the shut-off valve, so that with the said bushing, which is small and convenient to carry, and a key such as is 80 shown, a person is equipped to go from box to box and remove, adjust, or regulate the several plugs and valves, and will require no other tools or implements.

Much inconvenience to gas consumers especially and expense to gas companies occurs 85 in case of a break or leak in the street-box, and such break or leak is very liable to occur with the old style of boxes in the higher latitudes where frost penetrates to a great depth 90 and its action is correspondingly powerful. Thus, for example, suppose the pipes and 95 shut-off mechanism to be located four feet below the surface and the frost penetrates two or three feet, which is liable to occur any winter. The expansion of the earth or the lifting tendency of the frost would in that case be such as to raise and carry with it the upper part of the box, while the lower part would be held down by the pipes on either side. Then, 100 if there were no provision for this action, as there is none in the old boxes, something would have to yield, and a break and leak at the weakest point would be the result. This is a common occurrence in all cities, and it is 105 one object of my invention to overcome the difficulty by the extensible connection shown and described.

Having thus described my invention, what I claim as new, and desire to secure by Letters 110 Patent, is—

1. A street-box having a main supply-pipe, and two branch pipes leading therefrom, and each provided with channels to convey fluid directly from the source of supply, the supply-pipe and the branch pipe above it each being provided with a separate seat, and single valve constructed to occupy either of said seats, substantially as set forth.

2. In a street-box, a main supply-pipe, and 115 branch pipes leading from a common opening in said pipe, and one of said pipes being in a direct line with said opening, in combination with a single valve provided with two opposite seating-faces, and an internal fluid-channel having an induction-opening from the outside above said seating-faces, and located to control the flow of fluid through the opening in the main pipe and through the branch pipes, substantially as shown and described. 120 125

3. In a street-box and shut-off having two valve-seats, a valve between said seats pro-

- vided with a hollow neck and an opening above the seats leading into said neck, substantially as set forth.
4. In a street-box and shut-off, a double-faced valve having a hollow screw-threaded neck, a fluid-passage through said neck above the faces, and a seat for a turning key in said neck, substantially as set forth.
5. A street-box formed with a main-valve seat, a drip-orifice above the main-valve seat, and a valve-seat about said orifice, in combination with a main valve, and a plug separate from the main valve, and having a fluid-passage through it, and faced about its side to cover the drip-orifice, substantially as set forth.
6. In a street-box and shut-off having a main valve to control the fluid-supply, and formed with a chamber above said valve, with a drip-orifice at its side, in combination with a plug having a passage-way through it, and faced about its sides to cover the drip-orifice, with means to adjust the plug separately, substantially as set forth.
7. In a street-box, the casing provided with a drip-orifice above the main valve, and an annular shoulder, as a, above said orifice, in combination with a tube resting on said shoulder, and a plug provided with a fluid-passage through it, and faced about its sides to close the drip-orifice, substantially as set forth.
8. In a street-box, the casing provided with a main-valve seat, and a drip-orifice above said seat, and a chamber about the drip-orifice terminating in a shoulder in the casing, in combination with a tube resting on said shoulder, a main valve, and a plug adjustable in the said chamber to close the drip-orifice, substantially as set forth.
9. In street-boxes, a sectional bushing constructed with an irregular outer seating-surface, and each section having part of a key-seat formed on its inner face, in combination with a plug for the street-box, having an irregular seat for the bushing, whereby the bushing is prevented from turning, substantially as set forth.
10. In a street-box, a bushing consisting of two sections having lugs outside and faces inside shaped to form an angular key-seat when the bushing is set for use, in combination with a plug provided with a seat for said bushing, substantially as set forth.
11. In a street-box, a bushing formed in two sections connected by a spring, in combination with a plug for the street-box, provided with a seat in which the sections lock and form a key-seat, substantially as set forth.
12. In a street-box, a lower section rigidly connected with the supply-pipe, a separate upper section, and a tube sleeved and packed in said sections at its respective ends, whereby the upper section alone or with the intermediate tube may be raised, as by frost, without impairing the box, substantially as set forth.
